COATING MACHINE

Clifford E. Ives, Chicago, Ill., assignor to Sears, Roebuck and Co., Chicago, Ill., a corporation of New York

Application November 5, 1937, Serial No. 172,937

17 Claims. (Cl. 91—50)

My invention relates to the coating of sheet material, and more particularly to the coating of textile fabric. A special application of my invention is in connection with the manufacture of garments of the type described and claimed in the copending application of Richard H. Wann, Serial No. 87,868, filed June 29, 1936.

According to the above noted application, a garment such as a pair of overalls is provided with restricted reinforced and waterproofed areas, such as for example, the knee and/or seat portions thereof. The reinforcing and waterproofing material is usually applied in the form of an aqueous latex emulsion, although of course various other materials may be used for the purpose, and garments made in accordance with that invention have the advantage of being reinforced and waterproofed where required, without seriously adding to the weight of the garment or interfering with the comfort of the wearer, since the remaining portions are pervious to the passage of air.

In the fabrication of garments according to said invention, it is necessary that the reinforcing material be applied to a limited area, and it has been found most feasible to perform this operation in connection with a pre-cut section prior to sewing. It has also been found highly desirable in said coating operation to avoid the application of material to areas which are subsequently to be stitched through, since the stitching of reinforced areas results in the heating and breaking of needles, slowing up the work and involving considerable loss of labor and materials.

It is accordingly an object of my invention to provide a machine which will apply reinforcing material in liquid form to a restricted area of a pre-cut fabric section in such manner as to leave uncoated the marginal portions through which stitches are to pass.

A further object is to provide an entirely automatic machine for accomplishing the above mentioned operation.

Still another object is to provide such a machine which will be simple in construction, inexpensive to operate, and generally satisfactory for the desired purposes.

Another object is to provide an improved process for accomplishing the purposes above referred to.

In the application of separate coats of latex or the like, whether on a continuous piece of goods or on pre-cut individual pieces, bubbles, froth or foam form in the coating liquid adhering to the coating member upon separation of the coating member and the formed coat. Unless proper precautions are taken, the liquid thereafter fed to the coating member will contain such bubbles, producing unsatisfactory coats.

It is accordingly another object of my invention to provide an apparatus and process for maintaining free of bubbles the coating liquid fed to the coating member.

Various other objects and advantages will become apparent as the description proceeds.

Referring now to the accompanying nine sheets of drawings illustrating a preferred embodiment of my invention:

Fig. 1 is a top plan view of a machine embodying my invention;

Fig. 2 is a near side elevation thereof;

Fig. 3 is an end elevation thereof taken from the left end of Fig. 2, showing the receiving end of the machine;

Fig. 4 is a sectional view taken substantially along the line 4—4 of Fig. 1;

Fig. 5 is a sectional view taken substantially along the line 5—5 of Fig. 1;

Fig. 6 is a vertical cross-sectional view taken as indicated by the line 6—6 of Figs. 4 and 5;

Figs. 7 and 8 are vertical cross-sectional views taken as indicated by the lines 7—7 and 8—8, respectively, in Fig. 4;

Fig. 9 is a diagram of an electric hook-up for control mechanism embodying my invention;

Fig. 10 is a fragmentary enlarged view of the escapement mechanism appearing in Fig. 7;

Fig. 11 is a sectional view taken as indicated by the line 11—11 in Fig. 7;

Figs. 12 and 13 show the relative positions of coating-controlling cams corresponding to the arrangement of parts in Fig. 11;

Fig. 14 is a somewhat schematic fragmentary plan view showing the arrangement of a pair of panels to be coated, in relation to the coating means, corresponding to the arrangement of parts in Fig. 11;

Figs. 15 to 15L show schematically the relative positions of the coating means and the control mechanism therefor, together with the articles being coated, at selected points in a cycle of operation of the machine;

Fig. 16 is a view showing the relative positions of the coating control cams, taken as indicated by the line 16—16 in Fig. 7;

Fig. 17 is a fragmentary plan view of a device for stripping the coated material from the coating means, taken as indicated by the line 17—17 in Fig. 4;

Fig. 18 is an enlarged fragmentary transverse sectional view showing a panel being coated and pressed between the coating and presser rolls.

I provide a supporting frame comprising horizontal base members 10, horizontal members 11 spaced from said base members 10 by means of vertical supports 12 connecting the horizontal members at their ends and at intermediate points thereof, where required, and crossed struts 14 connecting opposite sides of the frame at the

ends and intermediate points thereof, as seen best in Fig. 3. The frame may be constructed of any suitable structural material having the required strength and it will be understood that, 5 although I show certain members as formed of angles, channels, strap metal, etc., various other shapes may be substituted if desired. This will apply of course to other structural elements described below. A plurality of cross bars T are 10 secured to the frame at the receiving end to form a table.

I provide a main source of power which may be in the form of an electrical motor 15, carried by a frame element 11, said motor having a drive 15 shaft 16 connected by any suitable means as, for example, a sprocket chain 17, with a sprocket 18 arranged on a shaft 20. Carried also on the shaft 20 is a sprocket 21 which engages a sprocket chain 23. The chain 23 is trained around a 20 sprocket 27 mounted on a stub shaft 28 (Fig. 6). Arranged on the run of the sprocket chain is an idler gear or gears 30.

Also keyed on the shaft 28 is a spur gear 31 which meshes with a gear 32 mounted on a shaft 25 33. The shaft 33 has keyed thereto at one end a spur gear 35 and at its other end a gear 36. The gear 35 drives a gear 37 fixed on a shaft 38, while the gear 36 drives a gear 34 arranged on a shaft 39. Keyed to the shaft 39 is another 30 gear 40 which drives a gear 41 mounted on a shaft 42.

Keyed on the shaft 20 is a gear 45 which drives a gear 46 on a shaft 47, as seen in Figs. 1 and 5. Also fixed on the shaft 20 is a gear 48 which 35 meshes with a gear 49 on a shaft 50. The idler 30 50 turns loosely on this shaft. The shaft 50 also carries a gear 51 which engages a gear 52 on a shaft 53.

The sprocket chain 23 also drives a sprocket 40 55 on a shaft 56 at the discharging end of the machine.

Fixed on the shaft 56 are pulleys 57 engaging 45 belts 58 which, as seen best in Fig. 1, extend substantially throughout the entire length of the machine.

At the receiving end of the machine the belts 58 are trained around pulleys 61 which are keyed to a shaft 62. Fixed approximately centrally on the same shaft is a grooved pulley 63 carrying a 50 plurality of belts 64, these belts being preferably round as shown.

Mounted on the shaft 62 is a sprocket 68 which 55 engages a chain 69, said chain actuating a sprocket 70 to which is eccentrically connected a piston rod 71 so as to reciprocate the latter to actuate a pump 72. This pump is designed to handle latex in the preferred embodiment and is 60 preferably of the diaphragm type. The belts 64 are trained at their forward ends around pulleys 74, which are loosely mounted for rotation on a stationary shaft 75.

The shaft 50 has keyed thereto a pulley or pair of pulleys 77 carrying conveyor belts 78, said belts being trained at their receiving ends over 65 pulleys 79 arranged for rotation on a shaft 80.

Also keyed to the shaft 56 are pulleys 82 carrying belts 83, the receiving ends of which are trained around pulleys 84 mounted for rotation on a shaft 85.

70 The coating liquid which is to be applied to the goods fed to the machine is moved by the pump 72 from the bottom of a tank 86 so that the liquid will be free of bubbles, through a pipe 87 and thence through a conduit 88 down into 75 a supply tank 89, the conduit, terminating near

the bottom of the latter tank to preclude formation of bubbles as the liquid issues from the conduit. Depending from the tank 89 is a nozzle 90 from which the liquid falls onto the top side of a blade 91 (Figs. 2 and 4) pivoted to a bracket 5 92 mounted as on a side frame member 11, a spring 93 urging the blade into engagement with a feed roll 94. The roll 94 preferably is formed of chromium plated steel, although other material may be found suitable. The blade 91 forms, 10 with the periphery of the feed roll 94, a fountain by which the said periphery is continually supplied with the coating liquid.

The liquid is fed by transfer from the feed roll 94 to a coating roll 95 which is preferably 15 fixedly mounted to rotate with the shaft 33 and is preferably soft and resilient and formed of vulcanized linseed oil, although other materials may be found suitable. The quantity of coating material fed by the feed roll 94 to the applicator 20 roll 95 may be regulated by varying the speed of the roll 94, as by changing the gear ratio at 40, 41 (Fig. 1). Screws 96 carrying suitable bearings 97 journaling the ends of the shaft 42 may be operated to adjust the feed roll 94 to engage 25 and disengage the applicator roll 95.

The material to be coated passes under the coating roll 95 and receives a coat therefrom. The coat may terminate completely as in the formation of separate coats, or partially, as in 30 the formation of a scalloped or sawtooth coat. In either event, when de-aerated liquid is applied, the liquid at the termination of a coat, as the roll separates from the goods, forms into bubbles, a negligible percentage of which remains 35 with the coat, the remainder adhering to the coating roll 95. As this part of the roll rises, it reaches the line of tangency with the feed roll 94, where the latter is descending. The feed roll 94 accordingly scrapes off all of the liquid and bubbles carried up by the roll 95, a drain trough 98 being disposed under the roll 94 to receive any 40 of this removed material not adhering to the roll 94 as the roll 94 passes over the trough. Such liquid and bubbles as are carried up by the under side of the feed roll 94 are then scraped off by 45 the doctor blade 91 and either adhere to the blade or fall therefrom into the trough 98.

The trough 98 is mounted to receive the excess liquid which flows over the ends of the blade 91. An overflow conduit 99 leads from a point slightly below the top of the supply tank 89 into the trough. The trough is preferably slightly inclined, and a pipe 100 (Fig. 2) extends from the lower end of the trough into the upper part of the tank 86, terminating over a strainer 101 in the tank. The bubbles remain for the most part in the trough 98, on the strainer and on the surfaces of the liquid in the tanks, the liquid being drawn from the tank 86 by the pump 72 from a point well below the surface of the liquid, so that the liquid pumped is substantially free of bubbles.

Thus it is seen that notwithstanding aeration 65 of the coating liquid adhering to the coating roll after each coating operation the bubbles are prevented from being fed to the coating roll. Such bubbles as are formed on the coat at the trailing end of the coat are of negligible quantity as has been stated, and disappear of their own accord 70 or are eliminated by squeeze rolls at the delivery end of the machine, as will appear. Thus all coats are substantially even and perfect, when delivered by the machine.

It will be seen from Fig. 4 that the shaft 39 75

is arranged directly below the applicator roll 95 and carries a presser roll 103. As seen in Fig. 6, the shaft 39 which carries the presser roll 103 is fixedly journaled at one end, as at 104, and interposed between the presser roll and the actuating gear 34 of its shaft 39 are universal joints 105. Lever arms 106x and 106y pivotally connect the shaft 39 on opposite sides of the presser roll 103 to the non-rotating shaft 75, and when these arms are raised the corresponding ends 103x and 103y of the presser roll may be moved into juxtaposition with the applicator roll 95 for pressing a sheet of material passing between the two rolls into engagement with the applicator roll.

15 Fixed to the shaft 38 is a conveyor roll 110 to move the coated fabric onto the belts 78.

Immediately beyond the run of the belts 78 as seen in Fig. 4 is a pair of squeeze rolls 112 and 113 arranged one over the other for cooperative relation with each other, said rolls being mounted, respectively, on the shafts 47 and 20. The rolls 112 and 113 are preferably formed of chromium plated steel. Each bearing for the shaft 47 may be adjusted vertically, for varying the space between the squeeze rolls, by means of any suitable adjustment device indicated generally by the numeral 114, including if desired, a spring permitting the rolls to separate and a wedge to prevent them from approaching each other beyond the desired degree. A stripper blade 115 carried by a bracket 116 is mounted for engagement with the squeeze roll 112. A conveyor roll 118 carried by the shaft 119 assists in transferring the coated fabric onto the belts 83.

The mechanism for controlling the presser roll supporting links 106x and 106y, and thus the application of the coating to the fabric, will now be described.

40 Pivotedly mounted on the frame at 121 below the links 106x and 106y are brackets 122 carrying actuating members 123x and 123y which engage the presser roll links 106x and 106y, respectively. Control levers 126x and 126y are pivoted at 127 and adjustably connected by screws 128 and 129 to the brackets 122, a spring 130 being associated with each screw 129.

45 The control lever 126x carries a cam follower 133x engageable with a cam X, and the control lever 126y has a cam follower 133y engageable selectively with any one of a plurality of cams, such as the cams Y, Y' and Y" (Figs. 4, 7, 12 and 13), the follower 133y, in the arrangement illustrated, being engaged with cam Y. The weight 50 of the presser roll 103, acting through the springs 130, causes the followers to yieldably engage the cams. The position of the presser roll is determined by the screws 128, and the pressure of the presser roll upward for the coating operation is determined by the springs 130, by which force 55 from the levers 126x and 126y due to the cams is transmitted to the presser roll. A stop or bumper bar 134 fastened to the frame limits upward swing of the levers 126x and 126y and hence 60 descent of the presser roll 103, as, for example, when the cams have been removed.

65 The cams are mounted to rotate with a tubular shaft 137 connected to the shaft 53 by a friction or other slip clutch 138 (Fig. 7). The clutch may 70 comprise face plates 140 and 141, which rotate with the shaft 53, and a cooperating plate 142 rotatable with the tube 137, the plates being pressed as by springs 143 into clutching engagement.

75 As has been pointed out, an object of my in-

vention is to apply latex coats to restricted areas having biased and unbiased edges on fabric.

It will be observed that the cams X and Y, acting through the levers 126x and 126y and the bars 123x and 123y upon the links 106x and 106y, control individually the elevation of the ends 103x and 103y of the presser roll 103. When this roll is fully raised and parallel to the applicator or coating roll 95, the full width of the coat is being applied to the fabric at once. When first one end 10 and then the other end of the roll 103 is raised (or lowered), the coat gradually widens from a point to the full width (or narrows from the full width to a point), the angle of the bias edge of the coat depending on, among other things, the speed with which the second end is raised (or lowered) for a given speed of feed of the fabric. In practice, leading and trailing edges of the coat may be formed parallel with the leading and trailing edges of the panels. 20

An overall leg panel or section of any suitable outline, as for example with one longitudinal edge on a bias and the other unbiased, may be placed on the conveyor belts 64 at the feed end of the apparatus as shown at the left in Figs. 1 and 14, 25 the panel P nearest the coating roll being arranged with its bias edge 145 leading and the following panel P' with its bias edge 146 trailing.

Arranged under the belts 64 (Fig. 8) are two pairs of electric lamps in a line normal to the 30 direction of conveyance of the panels, the end lamps 148x and 148y being utilized when men's leg panels are to be coated and the inner lamps 150x and 150y when boys' leg panels are to be coated.

The operation is the same in each case, so that the following explanation of the operation pertaining to the coating of panels for men's overalls will suffice for both.

The length of the presser roll 103 will determine the length of the coat, and may approximate the distance between the lamps used. This roll may be replaced by a shorter one of suitable length for coating boys' overall panels or by a roll 40 of other suitable length. 45

Positioned over the lamps is a shield 155 (Figs. 4 and 8) having holes 156 over the lamps to permit substantially only a pencil of light to escape upward from each lamp. Mounted in a housing 157 to receive the light through openings 158 is a 50 pair of mirrors 159x and 159y, adjustable so that light from one or the other set of lamps incident on said mirrors will be reflected through an opening 161 onto a photoelectric cell 162. Attached to each mirror is an indicator 163. Suitable indicia marked respectively "Men" and "Boys" are arranged so that when the words "Men" are indicated by both indicators 162, light from either or both of the end lamps 148x and 148y will be 55 reflected onto the cell, and when the words "Boys" are indicated by both indicators, light from either or both of the inner lamps 150x and 150y will be 60 reflected onto the cell. 65

A relay solenoid, indicated generally by the numeral 164, for controlling the rotation of the 65 cam shaft 137, is controlled by the cell 162 through any suitable hook-up, such as that illustrated in Figs. 7 and 9.

The relay comprises a switch arm 167, biased by a spring 167a, and two contacts 168 and 169 70 alternately engaged thereby, the solenoid 164, when energized, holding the arm engaged with the contact 169, and a spring 167a being operative, when the solenoid is de-energized, to hold the arm engaged with the contact 168. The arm 75

167 is connected to a current source as shown at 170. The contact 168 is connected to the coil of an electromagnet 171, having a movable core or armature 172 from which a pawl or stop 173 projects, the return wire 174 leading to the source of current as shown at 175. The contact 169 is connected to the coil of an electromagnet 177 having a movable core or armature 178 from which a pawl or stop 179 (Fig. 10) projects, the return wire 180 leading to the source of current as shown at 175.

15 Mounted to rotate with the tubular shaft 137 is a hub 181 (Figs. 7 and 11) carrying an escapement member 182 provided with a pair of teeth 183 and 184. When either of these teeth is engaged with the stop 173, rotation of the cam shaft 137 and hence of the cams X and Y is arrested, and the clutch 138 slips. The hub 181 also carries an escapement member 185 having a 20 pair of teeth 186 and 187 angularly displaced from the teeth 182 and 183. When either of the teeth 186 and 187 is engaged with the stop 179, rotation of the cam shaft 137 and hence of the cams X and Y is arrested and the clutch 138 slips.

25 The stops 173 and 179 are connected to the ends of a lever 188 pivoted at 188a (Figs. 9 and 10). When the relay switch arm 167 engages the contact 168, the stop 173 is withdrawn from engagement with the tooth 183, allowing the clutch 138 to turn the shaft 137. At the time the stop 173 is so withdrawn, it operates the lever 188 to project the stop 179 into the path of the tooth 186. Thus in this operation the cams X and Y are permitted to turn through the angle between the 35 teeth 183 and 186.

30 It will be noted that two brushes 189 are connected to a suitable electricity source and to the lamp 148y, and are mounted in such positions (Figs. 7, 9 and 11) as to be engaged for a limited 40 period in every revolution of the cam shaft 137 by a switch lug 190 carried by the hub 181 so that the lamp 148y is intermittently lighted. The lamp 148x is continuously lighted.

35 The relative positions of the cams X and Y, their followers 133x and 133y, the coating and presser rolls 95 and 103, a set of panels P and P' and the place at which the coat is applied, i. e., the coating line, the relay switch arm 167 and contacts 168 and 169, parts of the relay-controlled escapement mechanism, including the teeth 183, 186, 184 and 187 and the stops 173 and 179, at several selected points in an entire cycle, and the relative positions of the switch elements 189 and 190 controlling the lamp 148y at certain 50 of those points, will be understood upon reference to the following description and all or certain ones of schematic Figs. 15 to 15L. The lamp 148y appears in these figures only when it is lighted.

55 60 For convenience we may regard the cycle as commencing with a pair of mated uncoated panels arranged as shown in Figs. 1 and 14, the panel P nearest the coating roll having its bias edge 145 leading and the succeeding panel P' having its bias edge 146 trailing, just as the lamp 148x is eclipsed by the leading bias edge, the lamp 148y being dark since the lug 190 is spaced from the brushes 189, as is evident from Fig. 11. This eclipse accordingly has occulted the cell 162 and 65 thereby deenergized solenoid 164, the relay switch arm 167 has been swung by its spring 167a into engagement with the contact 168, energizing the magnet 171, pulling the stop 173 clear of the tooth 183, and projecting the stop 179 into the 70 path of the next escapement tooth 186 (Fig. 15).

75 At this occurrence the clutch 138 is about to commence turning the cam shaft 137 with the escapement members 182 and 185 and cams X and Y in the direction indicated by the arrow. At the commencement of this movement (Fig. 15) the 80 followers 133x and 133y are engaged in the valleys 191x and 191y of the cams X and Y at the points designated 0, and the leading point 192 of the bias coat edge 200 to be formed is a predetermined distance short of the coating line U of the 85 coating roll 95. The supporting bars 123x and 123y for the ends of the presser roll 103 at such time are accordingly in their lowermost positions, and hence the presser roll is spaced from the 90 coating roll and no coating occurs.

95 The movement of the cams proceeds for a limited time, during the early part of which the followers are dwelling in the valleys 191x and 191y of the cams, and accordingly the presser roll 103 remains in idle position. In the meantime the 100 panel P is approaching the coating line U and is covering the lamp 148x, the relay arm 167 remains engaged with the contact 168, and the escapement tooth 186 is approaching the stop 173. The valley 191x of the cam X terminates in an 105 abrupt outwardly projecting shoulder 193x, and the valley 191y of the cam Y terminates in a shoulder 193y of more gradually increased radius. When the follower 133x is depressed by the abrupt 110 shoulder 193x to the crest 198x, the bar 123x and hence the adjacent end 103x of the presser roll are quickly raised. At the commencement of this 115 rise the leading point 192 of the bias coat edge 200 to be formed has not quite reached the coating line U. When the rise is completed (Fig. 15-A), the end 103x of the presser roll 103 presses the panel P at the point 192 against the coating roll 95, leaving an uncoated stitching margin 196 of predetermined width. The coating pressure is 120 actually initially applied just before the crest 198x is reached by the follower 133x so that when it reaches the crest 198x a substantial coating pressure is applied, the coating roll being somewhat compressed or squeezed, the intensity of this 125 pressure being determined by the spring 130. It will be observed that at this beginning of the 130 coating operation the presser roll 103 is relatively sharply inclined (Fig. 15-A) so that substantially a point contact occurs between the panel and the 135 coating roll 95, the other end 103y of the presser roll being substantially at its bottom position because the follower 133y is just at the beginning of 140 its ride on the gradual shoulder 193y.

145 As the cams' rotation continues, the presser roll 140 end 103x remains elevated since the follower 133x dwells on the crest 198x, while the presser roll end 103y rises due to the engagement of the follower 133y with points of progressively increased radius along the slope 193y, thereby causing a gradual 150 lengthening of the line of contact of the coating roll with the panel P. Since this rise occurs while the panel is moving, it follows that the leading edge 200 of the area coated will be biased. The mechanism is so designed and timed as to 155 cause this bias edge of the coat to be substantially parallel with the bias edge 145 of the goods as shown.

160 Once the follower 133y becomes engaged with the crest 198y of the cam Y (Fig. 15-B), the full 165 length of the presser roll is elevated and causes the full width coating of the panel P. This full length engagement commences just before the follower 133y reaches the crest 198y, with merely a kissing pressure which is only momentary. 170

When the crest 198y is engaged by the follower 133y the coating roll is squeezed.

Shortly after the presser roll is fully elevated, the cams are arrested (Fig. 15-C) by engagement 5 of the tooth 186 with the stop 179, again causing the clutch 138 to slip, the panel P however continuing to move and be coated the full width. The effect of stopping the cams at this point while the coating continues is the same as would 10 be obtained if the cam crests 198x and 198y were longer and no stop occurred.

When the panel P has progressed so far as to 15 uncover the lamp 148x (Fig. 15-D), the light from the latter acts upon the cell 162 to energize the relay and move the relay switch arm 167 from the contact 168 to the contact 169, so as to retract the stop 179 clear of the tooth 186 and allow the clutch 138 again to turn the cams X and Y, the stop 173 now being disposed in the path of the tooth 184. During the early part of the ensuing 20 movement of the cams, their crests 198x and 198y are engaged by the respective followers 133x and 133y so as to hold the presser roll fully raised until the trailing unbiased edge 203 of the panel P is short of the coating line U by a distance equal 25 to the width of the trailing stitching margin to be left uncoated. When this point is reached, both ends of the presser roll 103 drop together, due to the movement of the cam followers from 30 the lands 198x and 198y down the abrupt shoulders 204x and 204y, to the second set of valleys 206x and 206y (Fig. 15-E), respectively, which valleys are adequately deep to insure complete retraction of the presser roll. When this occurs, 35 the next panel P' has not yet reached the lamp 148x, so that the relay arm 167 is not disturbed.

At this drop of the presser roll 103, or promptly 40 thereafter, and while the relay arm remains undisturbed, the tooth 184 is arrested by the stop 173 (Fig. 15-E), stopping the cams X and Y and causing the clutch 138 to slip again. Here again 45 the effect of stopping the cams is the same as though the cam valleys 206x and 206y had been longer and the rotation had continued, since no coating takes place and the panel P' continues to approach the coating line U.

The panel P has now progressed forward beyond the coating roll, and the succeeding panel 50 P', which may be the mate of the panel P and arranged with its unbiased edge 211 leading, is approaching the lamp 148x, the cams X and Y being at rest.

When the leading edge 211 of the panel P' 55 eclipses the lamp 148x (Fig. 15-F) the light to the cell 162 is occulted and the relay switch arm 167 is moved by its spring 161a from the contact 168 to the contact 169, energizing the magnet 172, which retracts the stop 173 clear of the tooth 184 60 and projects the stop 179 into the path of the next tooth 187, and allowing the clutch 138 to restart rotation of the cams.

As the rotation of the cams ensues, the switch lug 180 becomes engaged with the brushes 189, 65 lighting the lamp 148y (Fig. 15-G) while it, as well as the lamp 148x, is covered by the panel P', the presser roll being down because the respective followers 133x and 133y continue to dwell in the valleys 206x and 206y.

The unbiased edge 211 of the panel P' 70 may have passed the coating line U (Fig. 15-G) and, as the followers are depressed by the abrupt cam shoulders 213x and 213y, raising the presser roll, the edge 211 continues onward so that by the time the followers reach the crests

216x and 216y, respectively, of the cams X and Y, the leading coat edge to be formed is at the coating line U and the panel P' is pressed by the full length of the presser roll into engagement with the coating roll, commencing rearwardly 5 of the edge 211 such a distance as to leave uncoated the desired width of stitching margin 218. Just after this coating commences, the tooth 187 is arrested by the stop 179 (Fig. 15-H), stopping the cams and causing the clutch 138 10 again to slip.

For the following short period during the arrest of the tooth 187, and while the panel P' is being coated, the lamp 148y remains lighted but covered by said panel. As soon as the panel 15 P' uncovers the lamp 148y, the relay switch arm 167 moves from the contact 168 to the contact 169 (Fig. 15-I) and, when this occurs, the stop 179 is withdrawn from the path of the tooth 187 and the stop 173 is moved into the path of 20 the next tooth 183, allowing the clutch 138 again to become engaged and turn the cams.

During the early part of this turning of the cams, the presser roll 103 is held elevated by 25 virtue of the dwelling of the followers engaged with the crests 216x and 216y, and the coating of the panel P' continues for the full length of the presser roll. Before this full length coating ceases, and before the lug 190 leaves the 30 brushes 189 to darken the lamp 148y, the lamp 148x is uncovered by the trailing bias edge 146 of the panel P' (Fig. 15-J), so as to preclude interruption of the flow of light to the cell 162.

The cam X adjustably carries on a cheek 35 thereof a plate 220 (Figs. 12 and 16) having arcuately arranged slots 221 through which screws 222 extend into the cam. This plate has one end 223 disposed so as not to interfere with the shoulder 213x and has its outer edge arranged as a part of the crest 216x. The other end of this plate terminates in an abrupt drop-off shoulder 228x. The purpose of the plate 220 40 will appear presently.

It will be observed that the shoulder 228x 45 is disposed to reach the follower 133x after the gently sloping shoulder 228y of the cam Y reaches the follower 133y. Thus the end 103y of the presser roll commences to drop gradually as the gently sloping shoulder 228y passes by 50 the follower 133y, while the presser roll end 103x remains upraised. This results in a gradually shortened line of engagement of the coating roll with the panel P' and a consequent forming of a trailing bias coat edge 231 parallel to the trailing bias edge 146 and short thereof by the desired width of stitching margin 232. The coat edge 231 terminates at 233 (Fig. 15-K) when the abrupt drop-off shoulder 228x at the end of the crest 216x passes the follower 133x, dropping 55 the presser roll end 103x.

The cams then move a short distance to locate the followers 133x and 133y in engagement with the valleys 191x and 191y, respectively, at the point 65, the starting point of the cycle here described, where they are stopped by engagement of the tooth 183 with the stop 173, the relation of the parts at such time being shown in Fig. 15-L. The cams remain motionless until the lamp 148x is next eclipsed by a panel P, 70 whereupon the cycle will again commence as explained above in connection with Fig. 15.

Since the cams are shaped to cause the rolls to apply biases alternately leading and trailing, with intervening unbiased edges, care should be

taken that the panels be fed in the proper order and arrangement. Thus when the cams are arranged as shown in Figs. 12 and 13 in relation to their followers, the panels P and P' are in the order and arrangement (Fig. 14) which insures proper coating thereof.

To this end there is provided at the feed end of the apparatus (Fig. 1) a shaft 235 carrying a flag or signal device 236 which may have the general outline of a panel to be coated. This shaft may be suitably driven, as by a chain 237, from a sprocket 238 (Fig. 7) on the tubular cam shaft 137 and revolves once for every revolution of the shaft 137.

Since the tubular shaft 137 has intermittent motion, the flag shaft 235 will have like motion. The arrangement is such that during one stop, as, for example, when the tooth 183 is engaged with the abutment 173, the flag is disposed horizontally with its bias edge leading, signalling to the attendant that the next panel P to be fed should be placed on the conveyor with its bias edge leading. During the second stop of the cam shaft 137 thereafter, as when the tooth 184 becomes engaged with the abutment 173, the flag will be horizontal with its bias edge trailing, signalling to the attendant that the next panel P' to be fed should be placed on the conveyor with the bias edge trailing. The timing is such that the panels will then be coated in proper order, the flag serving at all times to show how the next panel to be fed should be arranged on the conveyor.

Since the control of the cam mechanism is dependent on the interruptions of the light beams to the cell 162, it is not necessary for the operator or attendant to adhere to any fixed time interval of feed of the panels. For example, if a panel is fed shortly before the flag reaches the horizontal, the interval between that panel and the next preceding panel will be shorter, so that, referring to Fig. 15-E, for example, the lamp 148x will be covered, and the relay switch arm 167 shifted, sooner, and consequently the period of idleness of the cams will be shorter. Thus the raising of the ends of the presser roll 103 will take place earlier and in fact will commence in time to coat the panel at the proper place behind the leading edge. If the panel is fed after an unusually great interval of time following the preceding panel, it will be seen from Fig. 15 that the relay switch arm and cams will be idle for a longer period, thereby delaying the raising of the presser roll to form the edge of the coat.

The number of auxiliary cams Y', Y'', etc., may be as great as the number of the various biases which may be desired, and the plate 220 may be capable of the corresponding adjustments, as will appear.

It may be that the panel demands a coat edge with a smaller or greater bias. The leading bias coat edge results from a gradual ascent of the presser roll end 103y after the roll end 103x is substantially completely elevated, and the trailing bias coat edge results from a gradual descent of the roll end 103y just before the roll end 103x falls. This explains why the cams are timed so that depression of the follower 133y by the gradual leading bias shoulder 193y commences, as at 240 (Figs. 12, 13 and 16), when the follower 133x substantially reaches the crest 198x of the cam X, and so that the follower 133x commences, as at 241x, its movement along the abrupt drop-off shoulder 228x when the follower 133y, moving

along the gradual trailing bias shoulder 228y, reaches the valley 191y of the cam Y, as at 242y.

It will be observed that the degree of bias varies directly with the magnitude of the time interval required for the ascent and descent of the roll end 103y, and hence with the angle subtended by the gradual bias shoulders of the cam engaged by the follower 133y. Thus, when the bias is to be small, the fall and rise of the follower 133y must be of correspondingly short duration, and when the bias is to be great the fall and rise of the follower 133y must be of correspondingly great duration. I have provided for purposes of illustration two cams Y' and Y'' auxiliary to the cam Y (Figs. 4, 7 and 16). The cam Y may be considered as one affording a medium bias, the cam Y' a smaller bias, and accordingly its bias-forming shoulders 193y' and 228y' subtend smaller angles than do the shoulders 193y and 228y, and the cam Y'' a greater bias, its bias-forming shoulders 193y'' and 228y'' subtending greater angles than do the shoulders 193y and 228y.

Since each leading bias action commences with the abrupt rise of the presser roll end 103x, and each leading bias cam shoulder 193y', 193y, 193y'' is adapted to commence engagement with the follower 133y at substantially the same time that the follower 133x reaches the crest 198x, it follows that the points of commencement of all of said shoulders lie in the same line, indicated by the point 240, the shoulder 193x of the cam X being used in each case.

Since, however, each trailing bias action terminates with the abrupt fall of the presser roll end 103x, and the trailing bias shoulders 228y', 228y, 228y'' are adapted to terminate their engagement with the follower 133y at different times, represented by the points 242y', 242y, 242y'', respectively, the drop-off shoulder 228x is made adjustable to locate the drop-off point thereof at the positions 241x', 241x (in full lines) and 241x''. This accounts for the provision of the adjustable cheek plate 220 on the cam X.

The cams Y', Y and Y'' may form an assembled unit adjustably splined on the shaft 137 so that any one of these cams may be selected and secured in place for cooperation with the follower 133y, the corresponding adjustment of the cheek plate 220 being made also.

It will be appreciated that if non-identical coats are to be formed in each cam revolution, or if the width of the stitching margins is to be varied, the various cam shoulders may be located in advanced or retarded positions, as conditions may require, to secure correct timing, as will be apparent to one skilled in the art.

When no coating is taking place, the presser roll is free of the coating roll. It is desirable to locate the lamps so that they will be eclipsed and revealed by the goods before the goods reaches the coating line. The distance of the lamps from the coating line determines to some extent the design of the cams. For example, referring to Fig. 15, the cams are just commencing to turn, and hence the first coating point, 192, must reach the coating line U when the follower 133x reaches the crest 198x (Fig. 15-A). Accordingly the angular extent of the valley 191x from the point 0 to the crest 198x must be in fixed relation to the distance from the point 192 to the line U.

Referring to Fig. 15-D, the cams are just commencing to turn, and the coating must stop short of the unbiased trailing edge 201 of the panel P, so that there will be an uncoated margin 202 back

of the coat edge 203. Accordingly the cams are so designed that the angular extent of the crests 198x, 198y from the point 0' to the drop-off shoulders 204x, 204y must be in fixed relation to the distance from the edge 203 to the coating line U, and it will be observed that this angular extent is less than the first angular extent by the angular extent for forming the stitching margin 202. This difference will be discerned readily upon reference to Figs. 15 and 15—D.

Fig. 15—F is analogous to Fig. 15 but relates to the next panel P', the cams being engaged with the followers at 0'' and being about to commence turning. The angular extent of the valleys 206x, 206y, from the point 0'' to the crests 216x, 216y, accordingly should be the same as the corresponding angular extent of the valleys 191x, 191y.

Fig. 15—J is analogous to Fig. 15—D but relates to the panel P', the cams being engaged with the followers at 0''', about to commence turning. The angular extent of the crest 216x from the point 0''' to the abrupt drop-off shoulder 228x accordingly should be the same as the corresponding angular extent of the crests 198x, 198y.

How long the cams should pause with the followers at the points 0' and 0'', when the panels are being coated, depends on the dimensions of the panels themselves, in the direction of conveyance, since each such pause terminates when the trailing edge of a panel uncovers a lighted lamp. In Fig. 15—C the cams have just stopped by virtue of the engagement of the tooth 186 with the stop 179, and it is evident that the length of time the cams will remain still depends on the distance of the trailing edge 201 from the lamp 148x, in the direction of conveyance of the panel. Were the dimension of the panel in said direction greater or less, obviously the pause of the cams would be correspondingly greater or less.

The pause of the cams while each panel is being coated the full width, i. e., when the points 0' or 0''' of the cams, as the case may be, are engaged with the followers, will terminate when the trailing edge of the panel being coated reveals one or the other of the lamps 148x, 148y. As explained above, the angular length of the crests from said points to the drop-off shoulders is the same. The length of each set of crests is slightly greater than the extent just referred to, so as to insure the full rise of both ends of the presser roll 103 before the pauses commence. This excess may be of any desired magnitude. In fact, if the cams were sufficiently large or their speed suitably controlled relative to the speed of conveyance of the panels, the pauses might be dispensed with. But it is preferred to make use of the pauses because by this means the same cams may be employed irrespective of variations in panel sizes. It will be apparent from the foregoing that since the coating is continuous during the entire time of engagement of the followers with a set of crests, it follows that for a given size of panels the sum of the time of movement of the cams during engagement of a set of crests with the followers preceding a pause and the time of such pause is fixed. Hence if the first of these times is shorter or longer the pause is correspondingly longer or shorter. The crests of the cams accordingly may be alike or different within the limits noted.

When a different coat bias is to be formed, the proper cam Y, Y', Y'' is selected for engagement with the follower 133y and the plate 220 correspondingly adjusted on the cam X (Figs. 12 and 16). Here, again, the termination of each pause

of the cams will be governed by the size of the panels and, for a given size, the pauses at a given set of crests will be alike irrespective of the bias, the bias-forming shoulders alone taking care of the formation of both the leading and the trailing bias.

The pause of the cams with the followers at the points 0 or 0', when no coating occurs, depends on the space intervals at which the panels are fed. In Fig. 15—E it will be noted that the cams have just stopped due to engagement of the tooth 184 with the stop 173, and that this pause will continue until the leading edge 211 of the panel P' eclipses the lamps 148x. The interval between panels should be sufficiently great to insure that the tooth 184 reaches the stop 173, i. e., the followers engage the points 0''. If the interval be less than this minimum, the followers will reach the crest 216x, 216y too late so that the stitching margin will be too wide, and a defective panel coat will result. By properly feeding the succeeding panels, however, matters will be corrected since the coating is governed by the lights, which in turn are controlled by the panels. The interval may be as much greater than the minimum as desired.

The foregoing applies alike to the interval between the panels P and P', and between the panels P' and P.

In order to prevent adhesion of the panel to the coating roll when the presser roll is released, I provide a stripping device such as is shown in Figs. 4, 6 and 17. Referring more particularly to Figs. 4 and 17, the device comprises a frame 250 of sheet metal or the like, the feed end of which comprises preferably a resilient metal sheet or other spring means 251 attached to a fixed bar 252 and disposed above and inclined downward adjacent the discharge ends of the belts 64, along which the panels are conveyed, stopping short of the bottom of the coating roll 95. The opposite end 253 of the frame is preferably fixed and disposed beyond the bottom of the coating roll 95 and above the feed ends of the conveying belts 78 to leave clearance for the coated panels.

The ends 252 and 253 of the frame 250 may have scalloped edges as shown at 255 and 256, respectively, to which a cord or fine, preferably hair-like wire such as music wire, shown at 257, may be secured as by wrapping so as to provide closely spaced strands 258 generally parallel to the direction of conveyance of the panels and disposed between the rolls 95 and 103. The strands are disposed for the most part under the frame ends 252 and 253, and normally are held down taut and out of contact with the rolls 95 and 103 under the action of the spring means 251, as shown in Fig. 4, so that, when not in use, the strands are prevented from cutting or grooving the soft surface of the coating roll 95.

Fastened to the stationary shaft 15 carrying the pulleys 14 over which the belts 64 move are guide brackets 260 arranged to engage the under side of each panel as the panel progresses beyond the belts 64 (Figs. 1 and 4), and to guide the panel between the rolls 95 and 103 and under the strands 258.

When the leading edge of a panel has progressed to a point beyond the coating line of the coating roll 95 a distance equal to the width of the stitching margin, as has been explained, elevation of one or both ends of the presser roll takes place, according as the leading edge is biased or unbiased. The presser roll, in rising, forces the part of the panel thereover, together with the superimposed stripper strands 258, upward.

against the relatively yielding coating roll 95, forcing the strands to be embedded in, and the upper face of the panel to engage, the coating roll. The coating liquid flows around and under each wire strand and makes the coat substantially complete and perfect.

As the presser roll descends, the spring 251 depresses the strands 258, which strip the progressing coated portion away from the coating roll, 10 the coated panel moving over the conveyor roll 110 and thence onto the conveyor belt 78. From this belt the coated panel passes between the squeeze rolls 112 and 113, which thoroughly impregnate the covered material with the liquid coat, 15 and then the panel is carried to the delivery end of the machine by the belts 58 and 83. The squeeze rolls 112 and 113 will eliminate any bubbles which may have adhered to the coat upon its separation from the coating roll and which have 20 not disappeared before reaching the squeeze rolls.

When either or both ends of the presser roll drop, the strands 258, from which the upward pressure of said roll is removed, move immediately down away from the coating roll under the influence of the spring means 251, thereby stripping the panel free of the coating roll, so that only that panel portion held by the presser roll against the coating roll is coated, thereby insuring leaving uncoated the trailing stitching margin.

30 From the belts 58 and 83 the panels travel into a curing oven of any suitable type, as, for example, one of the type illustrated in my copending application, Serial No. 118,879, filed January 2, 1937.

I am aware that many changes may be made 35 and numerous details of construction varied through a wide range without departing from the principles of my invention, and I therefore do not purpose limiting the patent granted hereon otherwise than as necessitated by the prior art.

40 I claim:

1. A coating apparatus comprising a coating roll, a presser roll, means for conveying material to be coated between said rolls, and means controlled by the conveyed material for pressing together portions of the rolls of progressively varying length while the material is progressing between said rolls, to press portions of the material of progressively varying width against the coating roll.

50 2. A coating apparatus comprising a coating member, a presser member, means for conveying material to be coated between said members, means for effecting relative approach of said members to engage material therebetween, means for effecting relative separation of said members, and means holding the material out of contact with said coating member when said members are separated.

60 3. A coating apparatus comprising a resilient coating member, a presser member, means for conveying material to be coated between said members, yieldable means comprising relatively fine widely spaced strands normally disposed to guide and retain the material away from the coating member, means for moving said presser member and with it the material and guide means toward said coating member, to embed said strands in said coating member and effect engagement of the coating member with the material, and means 65 for retracting said presser member and thereby allowing said guide means to strip the material from the coating member.

70 4. A device for coating material, comprising a pair of smooth-surfaced rollers, one of which is a coating roller, means for feeding the material be-

tween said rollers, and means for effecting relative approach and separation of the rollers at one end thereof while the material is pressed between the opposite end of the rollers.

5 5. A coating apparatus comprising a coating roll, a presser roll spaced therefrom, means for conveying a piece of material between said rolls, mechanism for effecting relative approach of said rolls to coat the material, releasable means for preventing operation of said mechanism, a light source, a photoelectric cell adapted to be energized by the light from said source, means controlled by said cell for effecting operation of said releasable means, the beam of light between said source and said cell being disposed in 10 the path of conveyance of the material, means operative when said beam is intercepted for releasing said releasable means, and means timing said mechanism to effect said relative approach after a part of the material has passed the coating portion of the coating roll.

15 6. A coating apparatus comprising a coating roll, a presser roll spaced therefrom, means for conveying a piece of material therebetween, a photoelectric cell, light means arranged so that light therefrom reaching the cell intersects the path of the conveyed material, and mechanism controlled by said cell and rendered operative when the conveyed material intercepts and reveals said light, said mechanism being timed to 20 effect relative approach and subsequent separation of said rolls during the passage of a predetermined intermediate portion of the material between said rolls.

25 7. An apparatus for applying a leading bias coat to a panel having biased and unbiased edges and fed with the biased edge leading, said apparatus comprising a coating roll, a presser roll, means for conveying the panel between said rolls, a pair of cams to effect relative approach and separation of the respective ends of said rolls, one at the wide and the other at the narrow side of the panel, said other cam being shaped to effect a gradual approach of said rolls at the narrow side of the panel after the opposite ends of the rolls are brought together by said one cam, driving means for said conveying means and cams, said driving means being timed to operate said other cam to press the corresponding 30 ends of the rolls together when the leading point of the leading bias adjacent the wide side of the panel is at the bottom of said coating roll, said other cam being formed to complete the relative approach of the rolls at the narrow side of the 35 panel when a point of the bias adjacent the narrow side of the panel is at the bottom of said coating roll, said cams being formed and timed to effect complete separation of said rolls when the unbiased edge of the panel is adjacent the 40 bottom of said coating roll.

45 8. An apparatus for forming a bias edge coat on a panel having a bias border, comprising a coating roll, a presser roll, means for conveying a panel between said rolls, and controlling mechanism for said presser roll, said mechanism comprising a photoelectric cell, light-generating means arranged so that the influence of light therefrom on the cell will be altered by interception of said light by a predetermined part of 50 the bias edge of the panel before said part reaches the coating line of said coating roll, said mechanism being formed and timed to gradually shift one end of the presser roll relative to the coating roll while the other end of the 55

presser roll is pressing the adjacent part of the panel against the coating roll.

9. A coating apparatus comprising coating means, means for operating said coating means to form coats having leading bias edges and coats having trailing bias edges upon panels having portions shaped to correspond with such coats, means for conveying the panels to the coating means, and means controlled by said operating means for signalling whether the next panel to be fed should be placed on the conveying means with its bias edge leading or trailing.

10. A coating apparatus comprising coating means, means for operating said coating means to form coats having leading bias edges and coats having trailing bias edges upon panels having portions shaped to correspond with such coats, means for conveying the panels to the coating means, means controlled by said operating means for indicating whether the next panel to be fed should be placed on the conveying means with its bias edge leading or trailing, and means for preventing operation of said operating means when no panel is fed.

11. A coating apparatus comprising a coating roll, a single means for supplying coating liquid to said roll, and removing from said roll all liquid remaining on that portion thereof which has completed a coating operation, before said portion receives an additional supply of the liquid from said means, a reservoir, means for conducting the removed liquid to the reservoir, so that the liquid at the bottom of the reservoir is substantially de-aerated, and means for delivering the de-aerated liquid from said reservoir to said supplying means.

12. A device for coating material, comprising a pair of rollers, one of which is a coating roller, means for feeding the material between said rollers, and means for effecting relative approach and separation of the rollers at one end thereof while the material is pressed between the opposite end of the rollers.

13. A coating apparatus comprising a coating roll, a presser roll, means for conveying material to be coated between said rolls, and means for effecting relative and progressive approach of the axes of said rolls for pressing together portions of the rolls of progressively varying length while the material is progressing between said rolls, to press portions of the material of progressively varying width against the coating roll.

14. An apparatus for coating bias edge panels of different bias edge lengths, comprising a coating roll, means for interchangeably supporting pressure rolls of different lengths corresponding to different bias edge lengths for cooperating with said coating roll, a presser roll supported by said means, means for conveying a panel between said rolls, and mechanism for effecting relative approach and separation of said rolls, said mechanism comprising a photoelectric cell, a lamp, and a mirror arranged to reflect a beam from said lamp onto said cell, said lamp being arranged so that its beam will be intercepted by a predetermined part of the leading bias margin of a panel before the panel reaches the coating line of said coating roll, said mechanism being

formed and timed to press said margin between an end of the presser roll and said coating roll and to progressively press the bias margin between said coating roll and the remainder of said presser roll, when said beam is intercepted, 5 and to separate said rolls when said beam is not intercepted, another lamp operative selectively instead of the first lamp and spaced therefrom lengthwise of the bias edge when a different length presser roll is supported by said supporting means and a panel of correspondingly different bias marginal length is to be coated, said other lamp being arranged to throw a beam onto said mirror, and means for adjusting said mirror to reflect the second beam onto said cell, 15 said second beam being disposed to be intercepted by the corresponding predetermined part of the bias margin of the second panel to enable said mechanism, by means of said rolls, to apply a bias edge coat of different bias length to the 20 second panel.

16. A coating apparatus comprising a coating roll, means for supplying coating liquid to said roll, means for removing from said roll all liquid remaining on that portion thereof which has completed a coating operation before said portion receives an additional supply of the liquid from the supplying means, a reservoir into which the removed liquid is conducted, a lower reservoir, means straining the liquid from the bottom of the first reservoir to the upper part of the lower reservoir, an upper reservoir disposed above the first reservoir, means for delivering liquid from the bottom of the lower reservoir to a point below the surface of the liquid in the 30 upper reservoir, and means affording gravitational delivery of the liquid from the bottom of the upper reservoir to said supplying means.

17. A method of supplying used coating liquid in a de-aerated condition to a coating member 40 supplying device, comprising the steps of removing all coating liquid from that part of the coating member which has completed a coating operation, gravitationally straining the removed liquid over the contents of a reservoir of such 45 liquid, withdrawing the liquid from a lower part of the reservoir remote from the surface level of such liquid and delivering it to a second reservoir at a point substantially below the level of the liquid in the second reservoir, and gravitationally delivering liquid from the bottom of the second reservoir to the supply device for coating operations.

18. A coating apparatus comprising a coating roll, a presser roll spaced therefrom, means for 55 conveying a piece of material between said rolls, mechanism for effecting relative approach of said rolls to coat the material, releasable means for preventing operation of said mechanism, a light source, a photoelectric cell adapted to be energized by the light from said source, means controlled by said cell for effecting operation of said releasable means, the beam of light between said source and said cell being disposed in the path of conveyance of the material, and means operative when said beam is intercepted for releasing said releasable means.
